UNITED STATES PATENT OFFICE.

LESLEY R. TUFTS, OF CLEVELAND, OHIO, ASSIGNOR TO THE CLEVELAND FOLDING MACHINE COMPANY, OF CLEVELAND, OHIO, A CORPORATION OF OHIO.

SHEET-FEEDING MECHANISM.

Application filed April 13, 1925. Serial No. 22,659.

My invention relates to improvements in sheet feeding mechanism, and more particularly to structures of this class known as pile-feeders; the objects of said invention being to provide alternatively a slow or accelerated adjustment of the sheet-supporting table; greater ease in operating said table and an adjustable drag for the sheets supported thereon.

10 In structures of this type it is necessary to provide for handling piles or stacks of paper weighing as much as a ton, hence, it is an important matter to insure the ready handling of the paper and easy operation of the sheet feeding mechanism. In the pile-feeder herein shown as embodying my improvements, the sheet-supporting table is provided with a manual crank appliance adapted alternatively to raise or lower said table slowly or rapidly as occasion may require. Furthermore, it is provided with reversely cut worms for operating the elevating gears associated with said table, whereby the shaft is placed under tension and end thrust thereon is avoided. Moreover, a 25 parallel adjustment for the drag preferably employed upon the rear of the topmost sheet insures an even adjustable pressure adapted for the particular stock handled from time to time.

30 The structure and advantages of my improvements may be more readily explained in connection with the accompanying drawings, illustrating such pile-feeder, wherein:

35 Figure 1 is a view in side elevation of the pile-feeder, incorporating my improvements.

Fig. 2 is an irregular transverse sectional view on line 2—2, Fig. 1, and

40 Fig. 3 is a detailed plan view showing the drag with its adjustments, the topmost sheet and the side frames alining the paper.

45 Throughout the several figures of the drawings, I have employed the same characters of reference to indicate similar parts.

50 The general features of an improved pile-feeder may be gathered by inspecting Fig. 1, wherein the sheet-supporting table *a* is mounted intermediately of and made adjustable by the set of lateral supporting chains *c* extending over top and bottom sprockets *b*, *b'*. These sprockets are mounted upon longitudinal shafts *b''* terminating in the gears *b³* mounted for actuation by the worm shaft *d*. The worms *d'* and *d''* thereon are 55 reversely cut, whereby, with the construction

shown, the shaft *d* is placed in tension, end thrust thereon is avoided, and the operation of the supporting chains is rendered relatively easy.

I have shown an improved type of operating mechanism for said shaft, which is not of my invention, but is set forth and claimed in the application of Olson, Ser. No. 63,883, to which detailed reference may be made. Essentially, this comprises a ratchet *e* mounted at the end of shaft *d* to effect its intermittent rotation when engaged by the pawl *e'*, rocked at one end of the frame *e''*, and connected with the driven crank arm *e³* by means of the connecting rod *e⁴*. Thereby the worm shaft *d* is turned in a counterclockwise direction for the purpose of gradually elevating the sheet-supporting table *a* by means of its lateral chains. Since the weight is balanced between opposing chains and transmitted to the reversely cut worms *d', d''*, there is no end thrust with the accompanying friction or cramping action at the terminal bearing. When the loaded sheet-supporting table is to be raised or lowered a handle *f* is placed upon the end of shaft *d* and rotated to actuate the worms and gears at a relatively slow speed, as required for handling heavy loads of paper. However, if it is desired rapidly to elevate or lower the unloaded table, the handle *f* is placed upon the stub-shaft *f'* which is connected by multiplying gearing *f''* with the shaft *d* so that the latter is rapidly rotated for the corresponding actuation of the sheet-supporting table.

55 Adjustably attached to one of the side frames *g* there preferably is provided a longitudinal supporting-rod *g'* held in position by the thumb screw *g''*. A transverse rod *h* with its collar *h'* and thumb screw *h''* affords longitudinal adjustment for the drag *i* as best shown in Fig. 1. This comprises the parallel pivoted arms *i', i''*, along the former of which an adjustable weight *i³* is slidably mounted for depressing the rubber faced drag *i*. This serves to place the necessary deterrent action upon the rear of the topmost sheet until it is withdrawn from beneath the drag by the rotary suction head *j* and thereby advance to the roller transfer table *k* at the left of the mechanism.

60 Further details of the mechanism shown do not require specific explanation inasmuch as they do not relate to my instant improve- 110

ments, but it will be understood from the foregoing that the sheet feeding mechanism is materially improved in construction and operation along the lines initially indicated 5 as contemplated by my invention.

Having now described apparatus exemplifying and embodying my invention, I claim as new and desire to secure by Letters Patent, the following:

- 10 1. In sheet feeding mechanism of the class described, the combination with a sheet-supporting table, means for vertically adjusting the same from time to time, and a rearwardly positioned drag comprising terminally pivoted links, a drag-member piv-

oted at the free ends of said links, and an adjustable weight associated with said drag, substantially as set forth.

2. In sheet feeding mechanism of the class described, the combination with an adjustable sheet-supporting table, of a drag appliance rearwardly associated with said table, comprising rectangularly adjusted members, parallel links pivoted thereon, a friction drag pivoted to the free ends of 25 said links, and an adjustable weight associated with the friction drag, substantially as set forth.

In testimony whereof I affix my signature.
LESLEY R. TUFTS
